UNITED STATES PATENT OFFICE

FREDRIC E. DOUGLAS, OF HOPEDALE, MASSACHUSETTS, ASSIGNOR TO DRAPER CORPORATION, OF HOPEDALE, MASSACHUSETTS, A CORPORATION OF MAINE

COP SKEWER FOR LOOM SHUTTLES

Application filed May 14, 1928. Serial No. 277,452.

This invention relates to thread carrier supports for loom shuttles and is more particularly directed to cop skewers for holding wound cops in the shuttle during weaving. It is now the ordinary practice to form cops of filling by winding a portion of the yarn or thread upon a short paper cop tube, leaving the major portion of the cop interior unsupported, and consequently liable on slight disturbance of its inner windings or coils to have the yarn or thread sufficiently disturbed to interfere materially with proper weaving conditions. During weaving the shuttle is suddenly impelled from one side of the loom to the other and suddenly arrested in each shuttle box, with the result that the wound cop is subjected to sudden disturbing influences calculated at times to cause the cop to move longitudinally from its supported position on the cop skewer.

It has been the practice heretofore, therefore, to provide cop skewers, whether of the single spindle or split type, with barrel projecting portions formed in some instances by a spiral or rib extending about and longitudinally along the cop skewer. Such spirals have been efficient in the discharge of their functions, but have introduced a disturbing influence upon the interior windings of the unsupported portion of the cop, because when the cop is pushed longitudinally on to the spiral portion of the skewer it is subjected to a lateral bending influence, first in one direction and then in another, as the cop and skewer are brought into their proper positions. This bending and disturbing influence on the interior windings of the unsupported portion of the cop is due to the fact that the single spiral as heretofore employed has its projecting portions at any point longitudinally of the skewer disposed opposite the concavity of the spiral on opposite portions of the skewer. As well known by those familiar with the character of wound cops, and bending action or disturbance of the interior windings by bending the cop, even to slight extent, is liable to result in sloughing of the interior windings, with the result that the yarn or thread will not be delivered properly from the cop during weaving and may

become broken or carry bunches of the yarn into the shed.

One of the purposes of the present invention is to provide a cop skewer with a plurality of spirals arranged side-by-side longitudinally of the skewer, so that when a wound cop is forced longitudinally of the skewer into its supported position thereon, the cop itself will not be laterally bent and the interior windings will not be disturbed. This is due to the fact that during the relative longitudinal movement of the improved skewer and cop in their assembly, the projecting portions of the plural spirals will act conjointly and at the same time upon the same section of the interior windings of the cop, thereby preserving its longitudinal axis and interior windings undisturbed.

Another feature of the invention consists in providing a cylindrical portion for the support of the paper cop tube, so that during the action of the feeler in a feeder loom, the feeler will be engaged by a cylindrical surface on the exterior of the paper tube, and in order to preserve the undisturbed relation of the interior paper tube and the cylindrical portion of the cop skewer, such portion of the skewer may be provided with a spiral rib which extends only slightly beyond the cylindrical surface of the skewer.

The invention and novel features thereof will best be made clear from the following description and the accompanying drawings of one good form thereof, it being understood that while a solid spindle cop skewer is shown and described in connection with the present invention, other types of cop skewers may be provided with the plural spirals arranged side-by-side longitudinally of the skewer.

In the drawings:

Fig. 1 is a plan view of portions of a filling replenishing shuttle showing the cop skewer of the present invention therein and also indicating by section the yarn windings and the paper cop tube;

Fig. 2 is a section on the line 3—3 of Fig. 1 showing only the cop skewer and windings thereon; and

Fig. 3 is a similar view on the line 4—4 of Fig. 1.

The cop skewer in the present instance of the invention is shown in association with a filling replenishing shuttle having a body portion 1 containing the usual filling chamber 2 and provided with holding jaws 3 which are adapted to engage rings 4 provided on the head 5 of the cop skewer, the construction being such that the cop skewer may be readily detached and ejected from the shuttle on replenishment of filling, as usual. The front wall of the shuttle is provided with an opening 6 through which the feeler may extend and feel for the filling in the shuttle on detecting beats.

As more clearly indicated in Fig. 1, the cop skewer is provided with a barrel portion 7 extending from the head 5 of the skewer and such barrel portion is provided with a plurality of spirals, two, 8 and 9, in the present instance, arranged side-by-side and extending longitudinally of the skewer.

The spirals 8 and 9 are of the same pitch, with the result that the projecting portion of each spiral, as indicated in Figs. 2 and 3, is disposed opposite the projecting portion of the companion spiral, and similarly the depressions 10 and 11 of each spiral are disposed opposite to each other, the result being that when the cop skewer and cop are forced relatively in a longitudinal direction, the projecting or shouldered portions of the spirals at each side of the cop will act at the same time upon opposite portions of the interior windings, so that the cop itself is not subjected to any bending or distortional strains calculated to injure the cop or its interior windings.

As indicated in Fig. 2, the interior of the cop, indicated by the windings *a*, is engaged at opposite points of the skewer by the raised portions 12 and 13 of the two companion spirals. In Fig. 3 the interior windings of the cop *a* are shown as engaged by the raised portions 12 and 13 of the two spirals at right angles to the position shown in Fig. 2, the two serving to illustrate the condition that occurs when the cop skewer and the cop are forcibly engaged by relative longitudinal movements thereof. In these same Figures 2 and 3, the interior windings of the cop *a* are shown between the raised portions 12 and 13 of the two spirals as substantially out of engagement with the depressed portions of the spirals, as at 14 and 15, and similarly in Fig. 3, at right angles to the position shown in Fig. 2, the depressed or recessed portions of the two spirals are shown as substantially out of engagement with the interior windings of the cop. The illustration afforded by Figs. 2 and 3 is somewhat exaggerated, for the purpose of making the characteristic operation clear when the skewer and cop are assembled.

In the construction shown as an instance of the invention, the two spirals 8 and 9 of same pitch extend along the barrel portion of the

skewer for a part of its length, and between the terminal portions of the two spirals and the head 5 of the cop skewer, the barrel of the skewer is formed cylindrical, as shown at 16, Fig. 1, for the support in cylindrical form of the paper cop tube 17, the result being that the paper cop tube will be maintained in its cylindrical shape for proper cooperation with the feeler of a feeler loom. This is an important feature, because by the cylindrical shape of the paper cop tube against which the feeler may contact when the filling is substantially exhausted on a detecting beat, the feeler will be caused to act more sensitively in the detection of substantial exhaustion of filling, which may thus be run from the shuttle with the production of a minimum waste of filling.

It may sometimes be desirable to provide the cylindrical barrel portion 16 of the skewer with a small spiral rib 18 which may act effectively on the inner surface of the paper cop tube to hold it in position notwithstanding the repeated shocks in the opposite direction to which the shuttle is subjected during weaving.

What is claimed is:

1. A cop skewer for loom shuttles for endwise assembly with a previously wound cop tube and cop having a head for securing the skewer in a shuttle, and a cop holding barrel portion provided with a plurality of separate spirals arranged side by side longitudinally of the skewer so that the exposed interior windings of the wound cop shall not be displaced as the wound cop is forced longitudinally upon the cop skewer.

2. A cop skewer for loom shuttles for endwise reception of a previously wound paper cop tube and cop having a head for detachable engagement with the shuttle, and a cop holding barrel portion provided with a plurality of separate spirals of the same pitch arranged side by side longitudinally of the skewer so that the exposed interior windings of the wound cop shall not be displaced as the wound cop is forced endwise onto the cop skewer.

3. A metallic cop skewer spindle provided with a head for detachable engagement with a shuttle and having a cop holding barrel provided with two separate spirals arranged side by side longitudinally of the skewer so that the exposed interior windings of the previously wound cop shall not be displaced as the wound cop is forced longitudinally upon the cop skewer.

4. A cop skewer formed as a metallic spindle and having a cop holding barrel provided with two separate spirals arranged side by side longitudinally of the skewer so that the exposed interior winding of a wound paper cop tube and cop shall not be displaced as the wound cop is forced longitudinally upon the skewer, and a cylindrical paper tube holding portion for presenting a cylin-

drical exterior of the paper tube to the feeler of the loom.

5. A cop skewer constituted as a metallic spindle and having a cylindrical portion provided with a rib to hold a paper cop tube, and a cop holding barrel portion provided with a plurality of cop retaining spirals arranged side by side longitudinally of the skewer so that the exposed interior windings of the wound cop shall not be displaced as the wound cop is forced longitudinally upon the cop skewer.

In testimony whereof, I have signed my name to this specification.

FREDRIC E. DOUGLAS.
